METAL WALL STUD

Percy N. Ashley, Leeds, Ala., assignor to
Vulcan Metal Products, Inc.

Filed Nov. 12, 1971, Ser. No. 198,505

Term of patent 14 years

Int. Cl. D25—01

U.S. Cl. D13—1 H

FIG. 1 is a plan view of a metal wall stud showing my new design;

FIG. 2 is an enlarged side elevational view taken generally along line 2—2 of FIG. 1, partly broken away;

FIG. 3 is a top plan view thereof drawn to the scale of FIG. 2; and

FIG. 4 is a sectional view taken generally along line 4—4 of FIG. 3.

I claim:

The ornamental design for a metal wall stud, substantially as shown.
